US00D448277B1

(12) **United States Design Patent** (10) Patent No.: **US D448,277 S**
Parker (45) Date of Patent: **** Sep. 25, 2001**

(54) **CASTOR**

(75) Inventor: **Kent Wallace Parker, Wellington (NZ)**
(73) Assignee: **Formway Furniture Limited, Wellington (NZ)**
(**) Term: **14 Years**
(21) Appl. No.: **29/130,360**
(22) Filed: **Sep. 28, 2000**
(51) LOC (7) Cl. **08-05**
(52) U.S. Cl. **D8/375**
(58) Field of Search .... D8/375, 374; D12/133; 16/34, 18 R, 18 CG, 39, 29, 45, 27; 190/18 A
